UNITED STATES PATENT OFFICE.

LEVI LLEWELLYN LEATHERS, OF ST. ALBANS, MAINE.

TROLLEY.

SPECIFICATION forming part of Letters Patent No. 744,770, dated November 24, 1903.

Application filed April 22, 1903. Serial No. 153,797. (No model.)

To all whom it may concern:

Be it known that I, LEVI LLEWELLYN LEATHERS, a citizen of the United States, residing at St. Albans, in the county of Somerset and State of Maine, have invented certain new and useful Improvements in Trolleys; and I do hereby declare the following to be a full, clear, and exact description of the invention, such as will enable others skilled in the art to which it appertains to make and use the same.

This invention relates to trolleys; and the object is to provide an improved guard so located and associated with relation to the trolley-wheel as to prevent accidental displacement thereof from the wire and which may also serve as a finder to assist the operator when applying the trolley to the wire.

A further object is to equip the trolley with means for normally holding the guard in proper operative position above the wheel, partially inclosing the wire and wheel, and permitting a constrained rotative movement thereto when the trolley passes beneath the cross or lateral supporting-wires of an overhead system.

For a full understanding of the merits and advantages of the invention reference is to be had in the following description to the accompanying drawings, wherein—

Figure 1 is a perspective view of my improved trolley applied to the wire. Fig. 2 is a longitudinal central section showing the parts assembled. Fig. 3 is a detail in perspective of the shaft on which the springs for holding the guard elevated are mounted.

In carrying out the invention I employ the usual trolley-pole 1, provided with a forked upper end 2, between which the trolley-wheel 40 is mounted for rotation. The arms comprising the fork are preferably made separate from the pole proper and secured in mortises formed on opposite sides thereof, as shown. The ends of the forked arms are provided 45 with apertures, one of which is threaded at 3 to receive the threaded end of a hollow journal 4, on which the trolley-wheel finds its bearing. This hollow journal or sleeve is interiorly screw-threaded a portion of its length, 50 as at 5, for the reception of a threaded annular shoulder, secured on the shaft 7, which is housed within the hollow journal.

The shaft 7 is formed with screw-threads 8, extending from one end thereof to a point near the center, and on this threaded portion 55 is secured a collar 9, which screws into the hollow journal 4 and holds the shaft rigid therein. The ends of the shaft are reduced to provide journals 10 for the guard-fingers 11, and the ends of the shaft are tapped for 60 the reception of screws 12, which serve to hold the guard-fingers on the shaft.

From the description thus far given it will be apparent that a hollow journal is provided for the trolley-wheel and held rigidly between the forked arms of the trolley-pole and that the shaft on which the guard-fingers are journaled is housed within the hollow journal and held against rotative and longitudinal movement, so that the guard-fingers are 70 mounted to rotate independently of the trolley-wheel.

For the purpose of holding the guard-fingers in a vertical position above the trolley-wheel and above the wire and to permit them 75 to have a constrained rotative movement downwardly and rearwardly from such position I provide coil-springs 13, which surround the shaft 7 on each side of the collar 9. One end of each spring is engaged in an aperture formed in the side of the collar 9, and 80 its other end extends into engagement with the guard-fingers, the latter being provided with an annular recess 14 and a longitudinal groove 15 on its face for this purpose, where- 85 by when the guard-fingers engage a lateral supporting-wire or other obstruction they are permitted to move downwardly and rearwardly against the tension of the springs 13; but as soon as they have passed such ob- 90 struction the springs will immediately act to return them to their upright position.

For the purpose of preventing the springs 13 from turning the guard-fingers too far, so that they would be thrown forwardly beyond 95 their perpendicular position, I provide stops 16, which consist of resilient members 17, fixed to the outside of the forked arms 2 and provided at their free ends with an offset portion or kink 18, adapted to engage a recess 19, formed in the periphery of the guard-fingers. These recesses 19 are arranged to align with the offset kink 18 when the fingers 100 reach a vertical position at right angles to

the wire during their flight upward after being displaced from such position by a cross-wire or other obstruction, and therefore the guard-fingers are restrained from further rotation.

5 The guard-fingers are preferably formed with inwardly-directed or reentrant portions 20, which partially envelop the periphery of the trolley-wheel, and their faces contiguous to the trolley-wheel are provided with anti-friction-rollers 21, against which the trolley-wire contacts when the wheel is displaced laterally therefrom by sharp turns in the route. 10 These antifriction-rollers reduce the abrasion on the wire and prolong its life. The diverging ends 22, formed by the reentrant portions 20, are adapted to serve as finders or rather assist the operator to engage the trolley-wheel with the wire, which operation is usually experienced with some difficulty, owing 15 to the tendency of the trolley-pole to spring upwardly above the wire. This inconvenience is avoided by the inwardly-directed portions 22, formed on the ends of the guard-fingers.

25 Having thus described my invention, what I claim, and desire to secure by Letters Patent, is—

1. The combination with a trolley-wheel, of 30 a guard therefor, a hollow journal for the wheel, and means in the hollow journal operating on the guard for normally holding the latter in operative relation to the wheel.

2. The combination with a trolley-wheel, of 35 a hollow journal therefor, a guard mounted for rotation independently of said wheel, a spring in the hollow journal for rotating the guard, and means for limiting the rotative movement of the guard.

40 3. The combination with a trolley-wheel, of a hollow journal for said wheel, guard-fingers mounted for rotation independently of said wheel, and means in the hollow journal acting on said fingers to normally hold them in a vertical position.

45 4. The combination with a trolley-wheel, of a hollow journal for said wheel, guard-fingers mounted for rotation independently of said wheel, means in the hollow journal acting on 50 said fingers to normally hold them in a vertical position, and means for limiting the movement of the fingers.

5. The combination with a trolley-pole and

its wheel, of a hollow journal for the wheel, a shaft fixed in the hollow journal, guard-fingers journaled on the shaft and having a bearing against the sides of the pole, and springs housed in the journal acting to rotate and hold the arms normally upward.

6. The combination with a trolley-pole and 60 its wheel, of a hollow journal for the wheel, a shaft fixed in the hollow journal, guard-fingers journaled on the shaft and having a bearing against the sides of the pole, and springs on the shaft inclosed by the hollow journal 65 for normally holding the guard-fingers upwardly and for returning them to their normal positions when dislodged therefrom.

7. In a trolley, the combination with the pole having a forked end, of a trolley-wheel 70 mounted for rotation between the forked ends and having a hollow journal, a shaft fixed within the journal, guard-fingers on the shaft mounted for rotation independently of the wheel, springs on the shaft inclosed by the 75 hollow journal and each having one of its ends fixed to the shaft and the other end to the guard, and means on the pole engaging the guard to limit its rotative movement.

8. In a trolley, the combination with a trolley-pole and its wheel, of a hollow journal for 80 said wheel, guard-fingers carried by the pole and mounted for rotation independently of the wheel, means in the hollow journal for rotating the guard-fingers and for normally holding them in a vertical position, and stops on the pole coacting with the guard-fingers to limit the movement of the latter.

9. In a trolley, the combination with the pole and its wheel, of a hollow journal for the 90 wheel, guard-fingers carried by the pole and mounted for rotation independently of the wheel, means housed in the hollow journal acting on the guard-fingers to hold them in an operative position above the wheel and to 95 automatically return them to such positions, and a resilient member on the pole engaging the guard-fingers to limit the movements of the latter.

100 In testimony whereof I affix my signature in presence of two witnesses.

LEVI LLEWELLYN LEATHERS.
